ABSTRACT OF THE DISCLOSURE

A method and apparatus for the installation of a water closet to a mounting base so that the water closet is structurally supported by the base, independent of all plumbing connections. The apparatus includes a lower flange which is mounted in or beneath the base so as to encompass a closet bend stub (the terminal portion of the drain system). An upper flange is mounted around a top portion of the closet bend stub and a resilient O-ring is disposed between the upper flange and the closet bend stub. A collar, formed on the upper flange, extends over the upper surface of the base, said collar having a pair of openings formed therein. A pair of fastening elements extending through the openings in the collar is attached to the lower flange. The fastening elements have an extended portion adapted for securing the water closet to the installation apparatus and, therefore, to the mounting base. The method includes the steps of mounting the lower flange around the bend stub by means of spacer rings, pouring the base, removing the spacer rings, and then installing the upper flange and the fastening elements.

BACKGROUND OF THE INVENTION

This invention relates generally to a method and apparatus for the installation of water closets, and particularly to a method and apparatus for the installation of water closets to a mounting base so that the water closet is structurally supported independent of all plumbing connections.

Insuring a reliable connection between a water closet and a plumbing drainage system has been a continuous and serious problem to the plumbing trade. Water closet installation methods in which the closet is structurally supported by the plumbing system, have presented difficulties in maintaining the seal between the closet fixture and the closet bend stub. Attempts have been made to alleviate this seal problem by pouring the concrete floor slab directly against the top of the bend, in concrete type floor installations; in wood type floor installations it has been attempted to tightly block the top of the closet bend to the floor system. However in both of these just described schemes, the quality and reliability of the resulting connection (seal) are dependent upon the workmanship involved in securing the closet bend to the floor system, and serious inspection problems exist. As a result of these inadequacies, revised building codes have been proposed in numerous locales which require that all floor mounted water closets be securely fastened to the mounting base independent of all plumbing connections. Another prior installation method includes a single ring flange for mounting a water closet thereto, with the ring flange being directly attached to the floor system. However once again a quality control problem is involved in preparing the floor system so that a secure connection between the flange and the floor may be obtained. Thus a method and apparatus for easily and reliably installing a water closet to a mounting base so that the closet is structurally supported independent of all plumbing connections, would be a significant contribution to the plumbing trade.

2

SUMMARY OF THE INVENTION

Briefly the water closet installation apparatus, in accordance with the principles of the subject invention, includes a lower flange mounted in or below a mounting base and encompassing a closet bend stub of a drainage system. An upper flange is mounted around the top of the closet bend stub, and the upper flange has a collar which extends over the top surface of the mounting base. A resilient O-ring is disposed between the upper flange and the bend stub. A pair of openings is formed in the collar and each one of a pair of fastening elements has a head adapted for passing through the openings in the collar and for engaging the lower flange. An outer end of each of the fastening elements, has a threaded shank which extends through the opening in the collar, and is adapted for mounting the water closet. The collar further has a plurality of holes, formed in the portion extending over the base, adapted for receiving attachment studs which secure the upper flange to the mounting base to provide additional lateral stability.

The installation method in accordance with the principles of the subject invention, includes the steps of mounting the lower flange around the bend stub by means of spacer rings, pouring the base, and then removing the spacer rings and installing the upper flange and fastening elements.

It is, therefore, among the objects of the subject invention, to provide a new and improved apparatus for securely mounting a water closet to a base so as to maintain the integrity and reliability of the plumbing connections.

Another object of the invention is to provide a new and improved apparatus for securely fastening a water closet to a mounting base so that the closet is structurally supported independent of all plumbing connections.

Another object of the invention is to provide a method for the installation of a water closet which increases the reliability of the seal between the water closet and a drainage system.

Still another object of the invention is to provide a method for the installation of a water closet which increases the reliability of the plumbing seals while reducing inspection problems.

Another object of the subject invention is to provide an apparatus for the installation of a water closet which is both economical and efficient.

A further object of the invention is to provide an efficient, economical and reliable method for installation of a water closet to concrete and wood type mounting surfaces.

Another object of the invention is to provide a method for installation of a water closet so that the installation conforms to the latest proposed building codes and specifications.

Still another object of the invention is to provide a method and apparatus for installing a water closet so that the water closet is structurally supported solely by a mounting base with a minimum of stress on the plumbing seals.

With these and other objects in view, the invention consists in the construction, arrangement, and combination of the various parts of the device, whereby the objects contemplated are attained, as hereinafter set forth, pointed out in the appended claims and illustrated in the accompanying drawings.

65 BRIEF DESCRIPTION OF THE DRAWINGS

FIG. 1 is a fragmentary side elevational view of a water closet mounted to a floor system.

FIG. 2 is a longitudinal cross-sectional view of a lower flange and spacer flange mounted in a concrete type floor system in accordance with the method and apparatus of the subject invention.

FIG. 3 is a longitudinal cross-sectional view, partially in phantom, of a water closet mounted to a concrete type floor system by means of the installation method and apparatus of the subject invention.

FIG. 4 is a top plan view of a lower flange that may be utilized in the installation apparatus of FIGS. 2, 3 and 7.

FIG. 5 is a fragmentary cross-sectional view taken on the line 5—5 of FIG. 4.

FIG. 6 is a top plan view of an upper flange that may be utilized with the installation apparatus of FIGS. 3 and 7.

FIG. 7 is a longitudinal cross-sectional view, partially in phantom, of a water closet mounted to a wood type floor system by means of the installation method and apparatus of the subject invention.

FIG. 8 is a longitudinal cross-sectional view of a second embodiment of a lower flange and spacer ring mounted in a concrete type floor system.

FIG. 9 is a transverse cross-sectional view taken on the line 9—9 of FIG. 8.

FIG. 10 is a longitudinal cross-sectional view of a second embodiment of the installation apparatus of the subject invention.

FIG. 11 is a fragmentary transverse cross-sectional view taken on the line 11—11 of FIG. 10.

FIG. 12 is a longitudinal cross-sectional view of a second embodiment of the apparatus for mounting the water closet to a wood type floor system in accordance with the subject invention.

DESCRIPTION OF THE PREFERRED EMBODIMENTS

In the embodiments of the invention which has been chosen by way of illustration, there is shown in FIG. 1, a water closet 10 mounted to a mounting base 12 and connected to a drainage system 14 which includes a closet bend 16. Reference is directed first primarily to FIGS. 2 through 7 which illustrate one selected embodiment of the method and apparatus for installation of water closets in accordance with the subject invention. The first step of the installation method is shown in FIG. 2 wherein an inner spacer ring flange 18 is installed around the upper portion of a bend stub 20, and the spacer ring flange 18 terminates in an expanded section 22 that includes a collar 24. A lower flange, or O-ring closet flange 26, encompasses the stub 20 and is supported by the collar 24. An outer spacer ring flange 28 is mounted around the inner spacer ring flange 18 and above an inner portion of the lower flange 26. The floor slab 30, which may be of concrete type material, is then poured around the top of the closet bend stub 20. After the floor slab has cured, the spacer rings are removed. The spacer ring flanges 18 and 28 may be constructed of any suitable material, such as Styrofoam for example, and the Styrofoam spacer rings may be burned away after the floor slab has cured, thereby simplifying the removal step.

After the spacer rings 18 and 28 have been removed, an upper flange 32 is mounted around the upper portion of the stub 20 (FIG. 3). The upper flange 32 has a collar 34 which is adapted for extending over the upper surface of the supporting floor system 12 (or concrete slab 30). The central section of the upper flange 32 has a recess 36 formed therein. The recess 36 is adapted for containing an O-ring 38, which may be constructed of any suitable resilient material such as rubber, for example. As seen best in FIG. 6, the collar 34 has a pair of elongated openings 40 and 42 formed on opposite sides thereof and a plurality of holes 43 through 46 formed around the outer perimeter thereof.

Referring momentarily to FIGS. 4 and 5, the lower flange 26 has a pair of elongated openings 50 and 52 formed in opposite sides thereof. On the bottom surface of the flange 26, a pair of recesses 54 and 56 is formed

adjacent and normal to the inner portion of the openings 50 and 52 respectively.

A fastening element 58 has a square T-shaped head 60 which is adapted for passing through the openings 40 and 54 in the collar 34 and the lower flange 36, respectively. After the head 60 is positioned below the lower flange 26, it may be rotated approximately ninety degrees and then lifted so as to be retained in the recess 54. Similarly the fastening element 62 has a square T-shaped head 64 which is adapted for passing through the openings 42 and 52 in the upper and lower flanges 32 and 26 respectively, and for being retained in the recess 56. The shank portions of the fastening elements 58 and 62 extend through the openings 40 and 42 in the collar 34, and are threaded on the outer end thereof so that the water closet 10 may be secured by means of mounting nuts 66 and 68.

The lower flange 26 has a pair of holes 70 and 72 formed therein (FIG. 4) for conveniently mounting the flange 26 to a wooden type floor system 71 as shown in FIG. 7. A pair of wood screws 74 and 76 in conjunction with the holes 70 and 72, respectively, may be utilized to temporarily hold the lower flange 26 in position until the installation is completed. Also a pair of ring clips 78 and 80 may be used to maintain the heads of the fastening elements 58 and 62 in the recesses 54 and 56, respectively, until the water closet 10 is secured by the mounting nuts 66 and 68. The holes 43 through 46 are designed to receive screws (not shown) or mounting studs (not shown) for wood and concrete type floor systems respectively, so as to provide additional lateral support to the installation.

For installation of the water closet 10 to the concrete floor system 30 (FIGS. 2 and 3) in accordance with the principles of the subject invention, the lower flange 26 is supported by the inner spacer ring flange 18, and covered by the outer spacer ring flange 28 prior to pouring the concrete slab 30, as was explained previously. After the slab 30 has cured, the Styrofoam spacer rings 18 and 28 are burned away and the upper flange 32 is installed around the upper portion of the stub 20, with the O-ring 38 disposed therebetween. The square headed T-bolts 58 and 62 are next inserted through the openings 40 and 50, and 42 and 52, respectively. The bolts 58 and 62, after having been positioned so that the heads 60 and 64 extend below the lower surface of the lower flange 26, are then rotated approximately ninety degrees so that the heads are in line with the recesses 54 and 56. Fastening studs (not shown) may be driven into the slab 30 through the holes 43 through 46 to provide additional lateral stability to the installation. An outlet port 82 of the water closet 10 may be connected and sealed to the stub 20 by any conventional method, and the water closet 10 is secured to the floor 30 by means of the nuts 66 and 68, and the fastening elements 58 and 62. As the water closet is secured to the floor by tightening the nuts 66 and 68, the heads 60 and 64 of the fastening elements 58 and 62 contact the recesses 54 and 56 so that the water closet 10 is structurally supported only by the floor slab 30. The O-ring 38 provides lateral support to the stub 20, so as to minimize the stresses which could effect the seal between the port 82 and the stub 20.

The installation of the water closet 10 to the wooden type floor system 71 (FIG. 7) is similar to that just described for concrete type floors, except that the lower closet flange 26 is mounted beneath the floor and is temporarily secured thereto by screws 74 and 76. Also the spring clips 78 and 80 may be utilized to temporarily retain the bolt heads 60 and 64 against the recesses 54 and 56, respectively, until the installation has been completed by bolting the water closet to the flooring system by means of the nuts 66 and 68.

Reference is now directed to FIGS. 8 through 12 which illustrate a second selected embodiment of the method and apparatus for installation of water closets

in accordance with the subject invention. In the description of the second embodiment, parts substantially the same as those described previously are given like reference numerals and parts which are similar but significantly different are assigned like numerals followed by a distinguishing reference letter. The first step of the installation method for concrete type floors, is shown in FIG. 8 wherein a spacer ring flange 18a is installed around the upper portion of the bend stub 20. The spacer ring flange 18a terminates in an expanded lower section 22a which includes a collar 24a. In the upper surface of the collar 24a is formed an annular recess 19 of a generally semi-circular cross-section and the upper face of the collar 24a, exterior to the recess 19, defines a ledge 21. A lower flange, or O-ring closet flange 26a encompasses the stub 20 and is supported on the collar 24a. The lower flange 26a has a downwardly protruding semi-circular annular shoulder 27, and a downwardly protruding rectangularly shaped shoulder 29 formed in the lower surface thereof. The annular shoulder 27 is adapted for engaging the recess 19 and an annular channel 31 is defined by the shoulders 29 and 27 and is carried by the ledge 21.

The floor slab 30, which may be of concrete type material, is posted around the top of the closet bend stub 20. After the floor slab is cured, the spacer ring flange 18a is removed. The spacer ring flange 18a may be constructed of any suitable material such as Styrofoam, for example; and the spacer ring may be easily removed after the floor slab is cured, by burning away the Styrofoam material. As shown in FIG. 9 an inner surface 33 of the spacer ring flange 18a is corrugated so as to increase the ease of installing the spacer ring flange onto the stub 20 and to improve the rigidity of the resulting installation.

After the spacer ring flange 18a has been removed, the upper flange 32 is mounted around the upper portion of the bend stub 20 as shown in FIG. 10 and as was described previously relative to the first selected embodiment. It is noted that the O-ring 38a shown in FIG. 10 is convexly shaped on the side adapted for engaging and resiliently retaining the bend stub 20.

A fastening element 58a has a J-hook-shaped head 60a which is adapted for passing through the opening 40 in the collar 34 and for engaging the annular shoulder 27 formed on the lower flange 26a. Similarly the fastening element 62a has a J-hook-shaped head 64a which is adapted for passing through the opening 42 in the upper flange 32 and for engaging the annular shoulder 27 formed on the lower flange 26a. The shank portions of the fastening elements 58a and 62a extend through the openings 40 and 42 in the collar 34, and are threaded on the outer end thereof so that the water closet may be secured by mounting nuts as explained previously.

The lower flange 26a may have mounting holes such as mounting holes 70a formed in the channel 31 (see FIG. 11) for conveniently mounting the flange 26a to a wooden type floor system 71 as shown in FIG. 12. Wood screws such as screws 74a and 76a, in conjunction with the mounting holes, may be utilized to temporarily hold the lower flange 26a in the proper position until the installation of the water closet 10 is completed. As explained previously a pair of spring clips 78 and 80 may be used to maintain the heads of the fastening elements 58a and 62a in engagement with the annular shoulder 27 until the water closet 10 is secured to the installation structure.

With the exception of the engagement between the fastening elements 58a and 62a and the annular shoulder 27, the method of installation of the structure of the embodiment shown in FIGS. 8 through 12 is similar to that described previously for the structure shown in the embodiment of FIGS. 2 through 7.

Thus there has been described a method and apparatus

for economically and reliably installing a water closet to a floor system so that the water closet is structurally supported solely by the floor system. In accordance with the subject invention, the stresses on the seal between the water closet outlet port and the plumbing system are minimized to insure the integrity of the seal. While the invention has herein been shown and described in what is conceived to be the most practical and preferred embodiments, it is recognized that departures may be made therefrom within the scope of the invention, which is not to be limited to the details disclosed herein but is to be accorded the full scope of the claims so as to embrace any and all equivalent devices.

Having described the invention, what is claimed as new in support of the Letters Patent is:

1. An apparatus for mounting a water closet having an outlet port, to a base so that the outlet port may be connected to a drain pipe, said apparatus comprising: a lower flange adapted for encompassing the drain pipe and for attaching to the base below the upper surface of the base; an upper flange adapted for encompassing the drain pipe, said upper flange having a collar formed on the upper end thereof; and fastening means for connecting said lower flange, through said collar, to the water closet.
2. The apparatus of claim 1 wherein said lower flange has at least one opening formed therein, and at least one recess formed in the bottom surface thereof in communication with said opening; said collar has at least one opening formed therein; and said fastening means includes a bolt, having a head adapted for passing through said openings in said collar and said lower flange, and for being retained in said recess, and said bolt having a shank with a threaded end portion adapted for extending through said opening in said collar, so that the water closet may be bolt to the shank and thereby structurally supported by the base.
3. The apparatus of claim 2 wherein said openings in said collar and said lower flange are approximately of rectangular shape; said recess in said lower flange is approximately of rectangular shape, with said recess being approximately normal to said opening in said lower flange; and said bolt head is approximately of a rectangular shape.
4. The apparatus of claim 3 wherein said upper flange has an annular recess formed in the inner surface thereof, and further comprising a rubber O-ring adapted for mounting in said annular recess.
5. The apparatus of claim 1 wherein said upper flange has an annular recess formed in an inner surface thereof, and further comprising a resilient member adapted for mounting in said annular recess.
6. The apparatus of claim 1 wherein said base is a concrete type floor system, said lower flange is adapted for mounting in said concrete type floor system, and said collar has a plurality of holes formed therein whereby said collar may be secured to said floor system.
7. The apparatus of claim 1 wherein said base is a wood type floor system, and said lower flange has at least one hole formed therein, said hole in said lower flange being adapted for attaching said lower flange to the lower surface of said floor system; and wherein said collar has at least one hole formed therein whereby said collar may be secured to the upper surface of said floor system.
8. The apparatus of claim 1 wherein said collar has at least one opening formed therein: said lower flange has a shoulder formed thereon; and said fastening means includes a fastener having a head on one end thereof adapted for engaging said shoulder, and a shank on the other end adapted for extending through said opening in said collar so that the water closet may be attached to the other end of said fastener and thereby structurally supported by said base.
9. The apparatus of claim 8 wherein said shoulder

is an annular shoulder formed in a lower surface of said lower flange and said fastener is a bolt having a head of a hooked configuration.

10. An apparatus for mounting a water closet having an outlet port, to a base so that the outlet port may be connected to a drain pipe and the water closet structurally supported primarily by the base, said apparatus comprising:

a lower flange adapted for encompassing the drain pipe and for attaching to the base below the upper surface of the base, said lower flange having an annular shoulder formed in the bottom surface thereof;

an upper flange adapted for encompassing the drain pipe, said upper flange having a collar formed on the upper end thereof, with said collar having an outer portion adapted for extending over said base, and an inner portion with at least two openings formed therein; and

at least two fastening bolts, with each bolt having a head adapted for engaging said annular shoulder and a shank with a threaded portion adapted for extending through one of said openings in said collar, whereby said water closet may be bolted to said shanks so as to be structurally supported primarily by said base.

11. The apparatus of claim 10 wherein said upper flange has an annular recess formed in an inner surface thereof, and further comprising a resilient O-ring adapted for mounting in said annular recess.

12. The apparatus of claim 11 wherein said collar has a plurality of holes formed in the outer portion thereof, said holes being adapted for receiving mounting studs for securing said collar to said base.

13. The apparatus of claim 12 wherein said lower flange has a pair of holes formed therein, said holes being adapted for temporarily attaching said lower flange to the lower surface of said base.

14. The apparatus of claim 12 further comprising an annular channel formed in said lower flange adjacent to said shoulder, and wherein said bolt head is of a hooked configuration adapted for being received within said channel.

15. A method of installing a water closet having an outlet port, to a base so that the outlet port may be connected to a waste pipe and the water closet structurally supported primarily by said base, said method comprising the steps of:

mounting a spacer flange around said waste pipe, said spacer flange having a collar formed thereon;

mounting a lower flange on the collar of said spacer flange, so that said lower flange encompasses the waste pipe;

forming said base around said spacer flange and said lower flange;

removing said spacer flange;

mounting an upper flange so as to encompass the waste pipe, said upper flange having a collar formed on the upper end thereof, with said collar having an outer portion extending over a portion of the base;

connecting said lower flange, through said collar to said water closet.

16. The method of claim 15 wherein said spacer flange is composed of combustible materials and said removal step includes burning away said spacer flange.

17. The method of claim 15 wherein said lower flange has an annular shoulder formed thereon, said upper flange has at least one opening formed therein, and said connecting step includes the steps of: selecting at least one bolt having a threaded shank on one end and a hooked head on the other end; placing said other end of said bolt through the opening in said upper flange; and engaging the hooked head of said bolt on said annular shoulder in an anchoring arrangement so that the threaded shank projects above said opening in said upper flange.

18. The method of claim 15 further comprising the step of placing a resilient O-ring between the inner surface of said upper flange and the waste pipe.

19. The method of claim 15 further comprising the step of attaching the outer portion of said collar of said upper flange to said base.

20. A method of installing a water closet having an outlet port to a wooden type floor system having a waste pipe mounted through said system, so that the outlet port may be connected to the waste pipe and the water closet structurally supported by said base, said method comprising the steps of:

mounting a lower flange, having at least one hole formed therein, around said waste pipe below said floor system;

temporarily attaching said lower flange to the under surface of said floor system by means passing through said hole in said lower flange;

mounting an upper flange around an upper portion of the waste pipe, said upper flange having a collar formed on the upper end thereof, with said collar having an outer portion extending over a portion of the floor system;

connecting said lower flange, through said collar to said water closet.

21. The method of claim 20 wherein said lower flange has an annular shoulder formed thereon, said upper flange has at least one opening formed therein, and said connecting step includes the steps of: selecting at least one bolt having a threaded shank on one end and a hooked head on the other end; placing said other end of said bolt through the opening in said upper flange; and engaging the hooked head of said bolt on said annular shoulder in an anchoring arrangement so that the threaded shank projects above said opening in said upper flange.

22. The method of claim 21 further comprising the step of placing a resilient O-ring between the inner surface of said upper flange and the waste pipe.

23. The method of claim 21 further comprising the steps of attaching the outer portion of said collar of said upper flange to said base.
